HENRY HENLEY, OF SHOALS STATION, INDIANA

Letters Patent No. 91,626, dated June 22, 1869.

IMPROVEMENT IN FRUIT-DRIERS.

The Schedule referred to in these Letters Patent and making part of the same.

To all whom it may concern:

Be it known that I, HENRY HENLEY, of Shoals Station, in the county of Martin, and State of Indiana, have invented certain new and useful Improvements in Fruit-Driers; and I do hereby declare that the following is a full, clear, and exact description thereof, reference being had to the accompanying drawings, and to the letters of reference marked thereon, which form a part of this specification, and in which is represented a perspective section of my fruit-drier.

The object of this invention is to provide a cheap and suitable means for drying fruit, &c.; and to this end,

My invention consists in the employment of a pan or vessel, constructed substantially as will be herein-after described.

To enable others skilled in the art to which my invention appertains, to make and use the same, I will now proceed to describe its construction and operation.

In the accompanying drawing is represented my drying-pan, which is made by making or constructing a square frame, A, to the inner sides of which, a suitable distance below its upper surface, is secured a metal plate or top, B, as seen in the drawing.

C designates the bottom, which may be either made of wood or metal, and is secured to the opposite or lower side of the frame A.

This bottom is provided with a convex outer surface, as illustrated in the annexed drawing, in the cen-

tre of which bottom is made or constructed an opening or hole, D, through which steam enters the pan, when placed on an ordinary boiler.

The object of so constructing the bottom of the pan or drying-vessel is to allow the condensed steam in the pan to be conveyed back to the boiler.

E represents one-half of a boiler, to which is attached the pipe D. The steam from the boiler E passes up through the pipe D, and between the plates B and C, where, becoming condensed, it passes down the pipe D again into the boiler, in the form of water, the plate C being made concave on its upper surface, to insure the flow of the water back again into the boiler.

The fruit or articles to be dried are placed on the top of plate B.

Having thus fully described my invention,

What I claim as new, and desire to secure by Letters Patent, is—

The frame A, provided with plates B C, the upper surface of the latter being made concave, as described, in combination with the pipe D and boiler E, all constructed, arranged, and operated substantially as set forth.

In testimony that I claim the foregoing as my own, I affix my signature, in presence of two witnesses.

HENRY HENLEY.
